UNITED STATES PATENT OFFICE.

EDWARD B. FEASTER, OF BOSTON, MASSACHUSETTS, ASSIGNOR TO SACO-LOWELL SHOPS, OF BOSTON, MASSACHUSETTS, A CORPORATION OF MASSACHUSETTS.

TEXTILE MACHINE.

Application filed February 21, 1922. Serial No. 538,190.

To all whom it may concern:

Be it known that I, EDWARD B. FEASTER, a citizen of the United States, residing in Boston, in the county of Suffolk and State 5 of Massachusetts, have invented an Improvement in Textile Machines, of which the following description, in connection with the accompanying drawings, is a specification, like characters on the drawings representing 10 like parts.

This invention relates to textile machines of that class in which are employed a rotatable spindle, a spinning or twisting ring and a traveler mounted on said ring to be 15 revolved thereon by yarn, thread or cord wound upon a bobbin or spool mounted on said spindle.

The invention is especially applicable to machines of the character described, which 20 are employed for spinning or twisting the yarn, and in the present instance is shown as embodied in a twisting machine or frame to which it is particularly applicable.

Machines of the character described are 25 limited in their production to the speed at which the yarn can be drawn through the traveler by the rotating spindle, which in turn depends upon the amount of heat generated in the traveler by frictional contact of the traveler with the spinning ring 30 on which it is mounted and around which it is revolved. In twisting frames as now commonly constructed, a plurality of strands taken from individual sources of supply, 35 usually spools, are fed by positively driven feed rolls to the spindle and said strands are twisted into a single strand or cord by the revolving traveler and the rotating spindle. In spinning and twisting frames as 40 now commonly constructed and known to me, the traveler is mounted on a spinning ring which is stationary in the usual ring rail, and when the cord is placed under tension by the revolving spindle, the traveler 45 is engaged with the stationary ring at a given point or points of the traveler, and said point or points of the traveler remain in engagement with the ring while the machine is in operation. As a result friction 50 is created and the traveler becomes heated, and as the heating of the traveler is influenced by the speed at which the spindle is revolved, the speed of the spindle is limited 55 since, from a practical standpoint, it can not be revolved at a speed sufficiently high to

heat the traveler to a point or degree where the latter will weaken or otherwise damage the cotton or other yarn and in some cases burn and rupture the same and thereby interrupt the operation of the machine. In 60 practice with twisting machines as now commonly constructed for twisting, for example, spools five inches in diameter when full, it has been found that the spindles may be rotated with safety only from about 1800 65 to 2000 revolutions per minute.

The present invention has for its object to provide machines of the character described, in which the speed of the spindles may be greatly increased without danger 70 of heating the travelers to such extent as to weaken, damage or burn the fiber and therefore without danger of interrupting the operation of the machine, and with consequent increase in production of the machine. 75

To this end provision is made for periodically heating and cooling the traveler while the machine is in operation and without interrupting the latter, whereby the traveler may be revolved at a relatively high speed 80 for a predetermined length of time with one portion of the traveler in contact with the ring, and then revolved for another period of time with another portion of the traveler engaged with the ring and with the 85 first mentioned portion disengaged therefrom and cooled by the air through which it is revolved. This alternate heating and cooling of different portions of the traveler serves to localize the heat in different portions 90 of the traveler, and enables the traveler and the spindle to be revolved at a materially increased speed without interrupting the operation of the machine, and in practice the spindle speed has been increased to over 3500 95 revolutions per minute without detrimental effects.

In the present instance is shown a novel construction and arrangement of traveler and spinning ring preferred by me and with 100 which the desired results may be obtained.

The traveler herein shown is provided with a plurality of contact points, and the spinning ring herein shown is composed of a stationary ring and a movable ring cooperating therewith, and the contact points on the traveler are arranged with relation to the spinning ring so that some of said contact points are engaged with said spinning ring, while others are disengaged therefrom, 110

which condition or arrangement of the contact points is reversed by axially moving the movable ring.

Provision is made for automatically moving said movable ring.

These and other features of this invention will be pointed out in the claims at the end of this specification.

Fig. 1 is a perspective of a sufficient portion of a twisting frame embodying this invention to enable it to be understood.

Figs. 2, 3 and 4, details of the traveler shown in Fig. 1.

Figs. 5 and 6, details in section and elevation to illustrate the engagement and disengagement of different contact points of the traveler.

Fig. 7, a front elevation of the twisting frame shown in Fig. 1.

Figs. 8 and 9, details of the movable ring.

Figs. 10 and 11, details of the stationary ring, and

Figs. 12 and 13, details of the stationary and movable ring assembled together.

The twisting frame or machine illustrated in Figs. 1 and 7 is of usual or known construction except as will be hereinafter pointed out, and for the purpose of this invention, only a sufficient portion of the machine necessary for a clear understanding of the present invention is illustrated.

Referring to Figs. 1 and 7, *a* represents the stationary spindle rail upon which is mounted the spindles *b*, only one of which is shown, said spindle having the usual pulley *c* by which it is rotated. Cooperating with the spindles *b* is the ring rail *d* which is vertically reciprocated in a manner well understood. The ring rail *d* carries the spinning ring through which the spindle *b* is extended and with which cooperates the traveler through which the yarn or cord *e* is drawn as the latter is wound upon the spool or bobbin *f* mounted on the spindle *b* to revolve therewith. The yarn or cord *e* is passed through the eye of a guide 10 attached to a cross bar 12 of the framework of the machine, and is fed forward at a predetermined speed, by feed rolls 13, 14, 15, which are positively driven in a known manner so as to feed the yarn at the same speed or rate it is wound upon the spool. In the present instance, the spinning ring is composed of two rings or members 16, 17 shown detached in Figs. 8 to 13 inclusive. The ring or member 16 may be designated the stationary ring and the ring or member 17, the movable ring.

These rings or members are concentrically arranged, and preferably in contact with each other, and are further connected together so as to be handled as a unit while permitting movement of one with relation to the other.

In the present instance the outer or sta-

tionary ring 16 is provided with inclined slots 20, herein shown as three in number and arranged substantially 120° apart, and the inner or movable ring 17 is provided with three studs or pins, which extend into the inclined slots 20, and two of which marked 21 are made so as not to extend beyond the outer circumference of the stationary ring while the third pin or stud marked 22 is made long enough to extend beyond said circumference to afford means by which the inner ring may be rotatively oscillated with relation to the outer ring and at the same time be moved axially by the walls of the inclined slots 20 cooperating with the said 75 studs or pins.

In the present instance, the inner ring is rotatively oscillated by a path cam 23 in a plate 24 affixed to the spindle rail *a* or other stationary part of the machine.

The stationary and movable rings 16, 17, have cooperating with them a traveler, preferably of the construction herein shown and comprising a substantially triangular shaped body portion 25 provided with arms 26, 27 extended from the lower corners thereof and having a curved arm 28 extended from the upper end of said body portion. The body portion 25 is provided with a bent finger 29 which forms a guide for the yarn or cord *e* through which the latter is drawn by the spool *f* when the latter is rotated.

The arms 26, 27, are each provided with slots or recesses 30, 31, for the reception of the lower edges of the rings 16, 17 respectively, the bottom walls of said recesses constituting four contact points of the traveler, which are engaged with the rings 16, 17, as will be described.

The curved upper arm 28 extends over the inner ring 17 out of contact therewith and is designed to be engaged with and disengaged from the inclined upper surface 32 of the outer ring 16, and constitutes another contact point of the traveler. The body portion 25 of the traveler is provided with a lug or projection 33 which is engaged with and disengaged from the inner surface of the inner ring 17 and constitutes another contact point of the traveler.

It will thus be seen that the traveler is provided with a plurality of contact points, which in the construction herein shown are six in number, and these contact points are arranged with respect to each other and to the stationary and movable rings, so as to form two groups of three each. One group comprises the curved arm 28 and the bottom walls of the recesses 31 in the arms 26, 27, and the other group comprises the projection 33 and the bottom walls of the recesses 30 in said arms. These groups of contact points may be conveniently designated group 1 and group 2.

The contacts in group 1 cooperate with

both rings as represented in Fig. 6 and the contacts in group 2 cooperate with both rings as represented in Fig. 5 when the machine is in operation and the yarn or cord is under 5 tension, and the traveler under the influence of centrifugal force.

By reference to Figs. 5 and 6, it will be seen that when the contacts of group 1 are engaged with the rings 16, 17, as represented 10 in Fig. 6, the contacts of group 2 are disengaged from said rings, and when the contacts of group 2 are engaged with the rings as represented in Fig. 5, the contacts of group 1 are disengaged from said rings. 15 Further it will be noticed that the contacts of group 1 engage the upper portion of ring 16 and the lower portion of ring 17, and that the contacts of group 2 engage the inner surface of the ring 17 and the lower portion 20 of ring 16.

It will be also seen, that when the traveler is drawn around the spinning ring with contacts of group 1 in service as represented in Fig. 6, the heat generated is localized 25 in different parts of the traveler, to wit, at the end of the curved arm 28 and at the bottom walls of the recesses 31 in the arms 26, 27, and when the contacts of group 2 are in service as represented in Fig. 5, the heat 30 generated is localized at the projection 33 and at the bottom walls of the recesses 30 in the arms 26, 27.

Localizing the heat at a plurality of points in the traveler, and periodically engaging 35 and disengaging the said points, enables the traveler to be drawn around the ring at a materially greater speed for a given length of time without heating the traveler and the guide arm 20 thereof sufficiently hot to 40 weaken, damage or burn the yard or cord *e* and thereby rupture the same. It will also be observed that when the contacts of one group are in service, the contacts of the other group are out of service and are cooled by 45 the air through which they are revolved.

The periodic shifting of the two groups of contacts on the traveler is effected, as herein shown, by the path cam 23 in the plate 24, which path cam is shaped to effect 50 a limited rotary movement of the movable ring 17 alternately in opposite directions.

The rotary movement of the ring 17 in one direction causes the pins 21, 22 to travel up the inclined slots 20 in the stationary 55 outer ring 16 and thereby move the ring 17 axially upward into the position shown in Fig. 5, and rotary movement of the ring 17 in the opposite direction causes the pins to travel down in the slots 20 and thereby move 60 the ring 17 axially downward into the position shown in Fig. 6.

The cams constituting the walls of the cam path 23 are preferably of substantially 65 equal length and number, and therefore it will be seen that the periods of time groups

1 and 2 of contact points are engaged with the rings, are of the same length. In practice, it is preferred to shift the groups of contacts every four seconds.

The ring 16 may be held stationary in the 70 ring rail in any suitable manner as by screws 36, only one of which is shown in Fig. 1, which engage the top surface of the ring, and by a screw 37, which engages the outer circumference of the ring.

The ring rail *d* is provided with a slot 38 indicated by dotted lines in Fig. 1, through which the pin 22 is extended and which allows said pin to be moved by the path cam.

In operation with a twisting frame, such as herein represented, the traveler has been revolved about the spinning rings 16, 17, with the spindle *b* making 3500 revolutions per minute, and a cord composed of ten strands has been twisted and wound upon a 80 spool of five inches in diameter, without weakening, burning or otherwise injuring the fiber or cord, whereas with twisting frames of the construction known to me and commonly used, the maximum speed of the 85 spindles is about 1800 or 2000 revolutions per minute.

When the machine is in operation and the traveler is being drawn around the spinning ring at the relatively high speed, it is forced 90 outwardly under the influence of centrifugal force and effects the engagement of the arm 28 with the inclined surface 32 of the outer ring 16 when the movable ring 17 is in the position shown in Fig. 6, and when the movable ring 17 is moved axially up into the position shown in Fig. 5, the centrifugal force brings the projection 33 into engagement with the inner circumference of the ring 17, which prevents the contact arm 28 95 being moved out sufficiently far to engage the outer ring 16.

The rings 16 and 17 are preferably shaped substantially as herein shown, so that they 100 cooperate at their upper ends to form a gutter for the reception of lubricating material, preferably a non-fluid oil, and this non-fluid oil is softened more or less by the heat of the rings 16, 17, and also by the heat from the traveler arm 28, and runs downward between the rings, keeping them well lubricated and also lubricating the traveler contact points 30, 31.

In the machine herein shown, the cam plate 24 cooperates directly with the movable ring 17, in that the pin 22 is extended into the path cam 23, but it is not desired to limit the invention in this respect, as it is evident that all the movable rings of all the spinning rings carried by the ring rail *d* 115 may be operatively connected together and to a single cam, so that the latter will operate all the movable rings to simultaneously shift the travelers thereon. One embodiment 120 of the invention is herein shown, but it is 125 130

not desired to limit the invention to the particular construction shown.

Claims:

1. In a machine of the character described, in combination, a spinning ring comprising a stationary member and a movable member, a traveler revoluble on said spinning ring and cooperating with the members thereof, and means for moving one of said ring members while the traveler is being revolved to effect engagement and disengagement of different parts of the traveler with said ring members.
2. In a machine of the character described, in combination, a spinning ring having concentrically arranged members, one of which is movable rotatively and axially with respect to the other, means for positively effecting said movements of said movable ring member, and a traveler mounted on said ring and cooperating with said ring members.
3. In a machine of the character described, in combination, a spinning ring having a plurality of members, one of which is movable with relation to the other, a traveler mounted on said spinning ring and having a plurality of contact points engaged with said ring members in one relation of the latter, and having a plurality of different contact points engaged with said ring members in a different relation of the latter.
4. In a machine of the character described, in combination, a spinning ring having a plurality of members, means for moving one of said ring members with relation to the other, and a traveler revoluble on said spinning ring and cooperating therewith to be engaged by said movable ring member at one point in one position of said movable ring member and to be disengaged therefrom at said point and engaged therewith at a different point in a different portion of said movable ring member.
5. In a machine of the character described, in combination, an axially movable ring, a traveler revoluble around said ring and cooperating therewith to contact with the said ring at one point of the traveler in one po-

sition of the axially movable ring and to be disengaged therefrom at said point and to be engaged therewith at a different point in another axial position of the said ring.

6. In a machine of the character described, in combination, a ring, a traveler revoluble thereon, and means for effecting alternate engagement and disengagement of different portions of said traveler with and from said ring.

7. In a machine of the character described, in combination, a spinning ring, a traveler cooperating therewith and revoluble around said ring in contact therewith, and means for positively moving said ring axially in opposite directions while said traveler is in motion around said ring.

8. In a machine of the character described, in combination, a rotatable spindle, a ring rail movable lengthwise of said spindle in opposite directions, a spinning ring movable with said ring rail and movable axially independently thereof, and means for positively effecting a plurality of axial movements in opposite directions of said spinning ring during the movement of said ring rail in one direction.

9. In a machine of the character described, in combination, a traveler provided with a plurality of groups of contact points, a spinning ring with which said groups of contact points cooperate, and means for alternately engaging and disengaging said groups of contact points with and from said spinning ring.

10. A traveler for spinning rings comprising a body portion, arms extended from said body portion and provided with recesses, an arm extended from the upper portion of said body portion in the same direction as the first mentioned arms, a projection on said body portion extended in the same direction as said arms and between the same, and a bent arm attached to said body portion and forming a guide for the yarn.

In testimony whereof, I have signed my name to this specification.

EDWARD B. FEASTER.
